US0D1084994S

(12) **United States Design Patent** (10) **Patent No.:** **US D1,084,994 S**
(45) **Date of Patent:** **** Jul. 22, 2025**

(54) **PORTABLE POWER STATION WITH
INFLATOR**

(71) Applicant: **Shenzhen Fanttik Technology
Innovation Co., Ltd.**, Shenzhen (CN)

(72) Inventor: **Zhiqiang Liang**, Shenzhen (CN)

(73) Assignee: **Shenzhen Fanttik Technology
Innovation Co., Ltd.**, Shenzhen (CN)

(**) Term: **15 Years**

(21) Appl. No.: **29/896,762**

(22) Filed: **Jul. 7, 2023**

(51) LOC (15) Cl. **13-02**

(52) U.S. Cl.

(57) **CLAIM**

The ornamental design for a portable power station with inflator as shown and described.

DESCRIPTION

FIG. 1 is a front, left and top perspective view of a portable power station with inflator, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the portable power station with inflator that form no part of the claimed design.

1 Claim, 8 Drawing Sheets
